DESIGN FOR A CLOTHES BASKET

Flora I. Kyle, Des Moines, Iowa

Application August 29, 1941, Serial No. 103,079

Term of patent 7 years

To all whom it may concern:

Be it known that I, Flora I. Kyle, a citizen of the United States and a resident of Des Moines, in the county of Polk and State of Iowa, have invented a new, original, and ornamental Design for a Clothes Basket, of which the following is a specification, reference being had to the accompanying drawing forming part thereof in which—

I claim:

The ornamental design for a clothes basket, as shown.

FLORA I. KYLE.
